UNITED STATES PATENT OFFICE.

GEORGE I. ONIONS AND GODFRIED ADOLPHSON, OF BUFFALO, NEW YORK.

RADIATOR FOR COOLING FLUIDS.

989,185.

Specification of Letters Patent. Patented Apr. 11, 1911.

Application filed December 19, 1908. Serial No. 468,324.

To all whom it may concern:

Be it known that we, GEORGE I. ONIONS and GODFRIED ADOLPHSON, both citizens of the United States, and residents of Buffalo, 5 in the county of Erie and State of New York, have invented certain new and useful Improvements in Radiators for Cooling Fluids, of which the following is a specification.

10 Our invention relates to heat-radiators, of the type used in motor-vehicles for cooling the circulating fluid passing around the engine cylinder.

The primary object of our invention is the production of a highly efficient tube heat-radiator which can be more economically manufactured than radiators of a similar type now in use, and which provides in its construction for a more effective and durable 20 connection between the air-tubes.

Other objects are the provision of tubes which can be quickly and accurately assembled without the use of skilled labor and which, when assembled, present an even 25 front and rear surface; to provide combined strengthening and separating means at the ends of the tubes; to provide the walls of the tubes, at least in part, with diagonal grooves, and to otherwise improve on heat- 30 radiators with a view of reducing the cost of production while increasing its durability and efficiency.

With these objects in view, our invention consists in the construction, arrangement, 35 and combination of parts to be hereinafter described and particularly pointed out in the subjoined claims.

In the drawings,—Figure 1 is a front elevation of a radiator constructed according 40 to our invention. Fig. 2 is an enlarged horizontal section taken through a number of assembled tubes lying in the same horizontal plane. Fig. 3 is an enlarged vertical longitudinal section taken through a portion of 45 several horizontal rows of tubes. Fig. 4 is an enlarged detached perspective view of one of the separators or collars applied to the ends of the tube. Fig. 5 is an enlarged longitudinal section through one of said separators or collars. Fig. 6 is an enlarged section 50 through one end of one of the tubes. Fig. 7 is a detached perspective view of one of the tubes. Fig. 8 is a view of the blank from which the body of the tube is formed. Fig. 55 9 is an enlarged longitudinal section through

one end of a tube showing a modified form of separator.

Referring now to the drawings in detail, similar letters of reference refer to similar parts in the several figures.

The reference letter A designates the casting of the radiator having a dome or inlet-chamber B at its upper end, an outlet-chamber C at its lower end and air-chambers D at the sides. Within the space formed by said 60 chambers are air-tubes E so arranged and separated that spaces F are formed between them which serve as water-passages connecting the inlet-chamber with the outlet-chamber. The tubes are preferably arranged in 70 horizontal rows with the centers of the tubes of alternate rows in the same plane.

In order to form the water-passages F, suitable spacing-means must be employed at the ends of the tubes, and for this purpose 75 we provide each tube at opposite ends with spacing-devices or separators in the form of collars G which are slipped over the ends of the tubes with the collars of adjoining tubes in contact. These collars, in addition to acting as separators to form the water-passages F, also serve to strengthen the ends of the tubes where they are most liable to damage.

In order to assure proper placement of the collars G upon the ends of the tubes, they 80 have inwardly directed flanges H at their outer ends which bear against the edges of the tubes and serve as stops, so that in placing the collars on the tubes, it is simply 85 necessary to slip them onto the tubes until 90 said flanges strike the ends of the same. As the tubes are all of exactly the same length, a perfectly even front and rear surface is thus obtained for the block of assembled 95 tubes, without the exercise of any great care and without the employment of skilled labor.

As the metal of which the air-tubes are formed is very thin, it is desirable that the flanges H extend beyond the inner surfaces of the tubes, particularly owing to its being 100 rather difficult to form sharp angles on the collars with flanges extending only to the inner surfaces of the tubes. The portions of the flanges extending beyond the inner 105 surfaces of the tubes we recurve or bend inward, as at I, and this greatly strengthens the tubes and prevents the walls of the latter being bent or forced away from the outer 110 walls of the collars. Moreover, it greatly minimizes the possibility for leakage, to

which radiators of this type are susceptible when brought in contact with an object by collision or otherwise.

The tubes herein shown are of rectangular formation in cross-section; and are formed of thin copper blanks J having several longitudinal rows of diagonally-disposed grooves K, which are preferably arranged at an angle of forty-five degrees to the longitudinal, and when said blank is bent on the dotted lines L, shown in Fig. 8, to form the tube, the grooves will be on three sides of the tube. The grooves thus formed are on the inside of the tubes and as these grooves are stamped in the blank, they form ribs K¹ on the outer sides of the tubes. The grooves K cause a whirling motion of the air passing through the tubes and also increase the interior surface area, thus aiding considerably in cooling the water passing between the tubes. If desired, the tubes may be made hexagonal, octagonal, or given any other cross-sectional form; the spacing-collars being, of course, of corresponding formation. The sizes of the water-passages may be varied by using collars of thicker or thinner metal, as may be desired; and the tubes may be arranged in any position relative to each other, so long as the water-passage between the tubes connect the inlet-chamber A of the radiator with the outlet-chamber B thereof.

In Fig. 9, we have shown the flanges H on the collar terminating flush with the inner surface of the tube to which it is applied, but it will not be possible to provide the collar with such sharp angles, without an additional operation in the stamping of the same. In some cases this modified form may be desirable, and when cost of production is not considered, may be preferable to some-users, since it does not restrict the area of the openings through the tubes.

The collars may be made a tight fit over the tubes, or they may be soldered to the tubes; and in either case, after the collars are applied to the tubes, the latter are assembled into block form of the desired size and shape to fit into the casing of the radiator, and when so assembled and held together by suitable means with the exposed ends of the tubes in perfect alinement, the front and rear faces of the block of tubes are dipped into molten solder so that they unite in a secure and water-tight manner.

From the foregoing description, it will be understood that the heated water entering the radiator is delivered to the upper ends of the water-passages between the open-ended tubes. In passing through said passages, the water is cooled by the cool air passing through said tubes and escapes through the lower ends of said passages into

the outlet-chamber, from which it is delivered to the motor.

Having thus described our invention, what we claim is,—

1. A device of the character described having a plurality of assembled air-tubes; said tubes being united at their ends in a watertight manner, each tube having spacing collars fitting onto opposite ends and contacting with the collars of adjoining tubes to form water-passages between the tubes, said collars being bent inward over the edges of the material forming the tube and recurved to enter the tube.

2. A device of the character described having a plurality of assembled air-tubes, each tube having spacing-collars fitting onto opposite ends and having their inner sides in contact with said tubes and their outer sides in contact with the collars of adjoining tubes to form water passages between the latter, each collar having the outer ends of its walls bent inward to face the edges of said tubes.

3. A device of the character described having a plurality of assembled air-tubes, each tube having spacing-collars fitting onto opposite ends and contacting with the collars of adjoining tubes to form water-passages between the latter, each collar being bent inward over the edges of the tubes and provided with a short return portion fitting into the tube, said return portions being shorter than the walls of said collars.

4. A radiator comprising a plurality of parallel tubes each tube having its ends surrounded by collars which engage with the collars of adjacent tubes and each collar being provided at its outer end with an internal reversely-folded flange which turns around the adjacent end of the respective tube and engages with the inner side of the same.

5. A radiator comprising a plurality of parallel tubes of hexagonal form in cross section, and hexagonal collars arranged on the outer sides of the ends of each tube and engaging with their flat sides against corresponding flat sides of the collars of adjacent tubes and each collar having its outer end provided with a flange which is turned inwardly against the inner side of the respective tube.

In testimony whereof, we have affixed our signatures in the presence of two subscribing witnesses.

GEORGE I. ONIONS.
GODFRIED ADOLPHSON.
